UNITED STATES PATENT OFFICE.

CORNELIUS M. GEIGER, OF BEE RIDGE, FLORIDA; ASSIGNOR OF ONE-HALF TO THOMAS A. ALBRITTON, OF BEE RIDGE, FLORIDA.

SAFETY-COVER FOR GONDOLA CARS.

1,252,259.

Specification of Letters Patent.

Patented Jan. 1, 1918.

Application filed May 17, 1916. Serial No. 98,174.

To all whom it may concern:

Be it known that I, CORNELIUS M. GEIGER, a citizen of the United States, residing at Bee Ridge, in the county of Manatee and State of Florida, have invented certain new and useful Improvements in Safety-Covers for Gondola Cars, of which the following is a specification.

The present invention has relation to certain new and useful improvements in safety covers for gondola cars and other open top railway rolling stock; and as its primary object contemplates the provision of a novel device of this nature that is readily attachable and detachable to and from the car and, which when in place will permit of the loading or unloading of the car in the usual manner.

A further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended claims.

In the accompanying drawings wherein like characters designate like parts throughout the several views:

Figure 1 is a view in side elevation of a gondola car of substantially the conventional form showing my invention as applied thereto, in its preferred embodiment;

Fig. 2 is a view in top plan of my improved safety cover;

Fig. 3 is a fragmentary view showing the opposite cover members in an elevated position;

Fig. 4 is a view showing the body of the cover with the movable cover members detached therefrom;

Fig. 5 is a view showing an improved form of connecting joint that is used;

Fig. 6 is a view of another form of connecting joint that is employed;

Fig. 7 is a fragmentary view of the carry-

ing frame showing means to lock the same in connection with the respective car body and.

Fig. 8 is a view similar to Fig. 7 showing more clearly the means for locking the cover in position.

In the drawings A designates a car body, of substantially the conventional form, in connection with which my present invention is shown.

My invention is readily applicable to other forms of car bodies, and different types of railway rolling stock, such as will be apparent from the following.

In reducing my invention to practice I first provide a carrying frame 10, of a durable metal, which is preferably of a dimension whereby it will fit snugly about the upper portion of the car body, such as shown in Fig. 1, and when in place, rests upon a series of equidistant supporting studs 11. The ends of the frame 10 are provided with a pair of substantially vertical rods or standards 12 (see Fig. 2) each of which carries a joint or connection 14, one of which joints is separately illustrated in Fig. 5.

Each joint 14 includes downwardly slanting sleeves 15, for connection with oppositely projecting end rods 16 and 17 that are connected at their lower ends to the side portions of the frame 10, in a suitable manner; and each joint 14 is also provided with an upwardly directed sleeve 18 for accommodating the lower end of a securing rod 19. Intermediate its ends, the securing rod 19 above referred to is supplied with oppositely directed securing arms 20 (see Fig. 3) whereby it may be utilized to retain certain of the cover members in an elevated position at certain times.

Each joint 14 further carries an inwardly directed sleeve 21 (see Fig. 4) that receives one end of one of the supporting rods 22 and 23, the inner ends of the latter being connected by still another joint or connecting member 24 such as shown in detail in Fig. 6.

The joint 24 carries downwardly directed sleeves 25, for connection with the upper ends of stay rods 26 whose lower ends are affixed to the frame 10 in the usual manner, and this joint further carries an upwardly directed sleeve 27 for receiving the lower end of a rod 28 similar to the rod 19 above referred to. The rod 28 is provided with oppositely directed securing arms 29, similar

to the arms 20, before mentioned, whereby it may also co-act with the rod 19 in retaining the cover members in an elevated position. The joint 24 further carries down- 5 wardly directed sleeves 30 which receive the upper ends of simple stay rods 31 and 32, the lower ends of the latter being connected with the end portions of the frame 10 in a suitable manner, as shown in Fig. 3.

10 I now provide the end rods 16 and 17 with inwardly directed supporting ledges 33 and 34 while the side members of the frame 10 carry like supporting ledges 35 and 36 in order to adequately support the several cover 15 sections in the manner subsequently appearing.

Throughout their longitudinal extent, the side members of the frame 10 are provided with spaced openings 37 (see Fig. 8) adjacent which are arranged paired bearings 38 to receive pintles 39. Cams 40 are mounted to be movable with respect to the said pintles and operate in the respective openings 37, each cam 40 being provided with a 25 suitably directed handle 41, whereby they may be conveniently manipulated. In other words, when the cams are in the position shown in dotted lines in Fig. 8 the frame 10 may be quickly and easily arranged in position 30 on the respective car body or removed therefrom, as the case may be. However upon moving the cams into the position shown in full lines in the said figure the same will be brought into binding engagement 35 with the sides of the car body thereby securely locking the same against removal and providing for the stability of the device during movement of the rolling stock. This construction also provides for the secure 40 detainment of the several parts of the device in position during movement of the car so as to effectually prevent rattling and the consequent premature breaking of the elements.

45 The cover members of the device preferably consist of a series of spaced carrying members 42 having their inner ends curved as at 43 to embrace the carrying rods 22 and 23 above referred to, while their outer ends 50 are connected through the instrumentality of a series of links or connecting portions 44 in conjunction with elbows or other joints 45. The members 42 may be covered with a section of reticulated fabric, such for instance as mesh wire or the like, such as 55 shown at 46 whereby they will adequately guard against theft of the contents of the car yet at the same time permit a free circulation of air and a direct view of the contents. The several cover sections are designated 60 in their entirety in the present embodiment by the numerals 47, 48, 49 and 50 respectively.

65 When in a closed position, the respective cover members rest on the ledges 33, 34 and

35 respectively in the manner as clearly shown in Figs. 1 and 2 so that when in such position the hasp 51 thereof may be locked to the frame 10, as shown at 52. On the other hand when in an elevated position the 70 ring 53 of the said cover members may be engaged with any of the securing arms 20 or 29 such as shown in Fig. 3 whereby they will be securely held against accidental dislodgment. When in an elevated position the 75 covers will permit of the loading or unloading of the car, in the usual manner.

From the foregoing it will be recognized that I have provided a device of the nature in question that is readily applicable to conventional forms of railway cars, one that obviates impeding either the loading or unloading of the car when in place, and finally one that may be manufactured at a comparatively low cost. In view of the fact that 85 the advantages and novel features of my invention appear to be apparent from the foregoing it is believed that further details of the description is unnecessary.

In reducing my invention to practice I 90 find that the form referred to herein as the most practical and preferred embodiment is the most efficient; but realizing that certain conditions will necessarily vary in concurrence with the adoption of my device, I 95 desire to emphasize the fact that various minor changes in the details of construction and in the proportion of parts may be resorted to when required without sacrificing any of the advantages of my invention as 100 defined in the appended claims.

Having thus fully described my invention, what I claim as new and desire to secure by Letters Patent, is:

1. In a safety cover for gondola cars, a 105 frame devised to be removably attached to the car body, a supporting structure carried by said frame, and a series of independently movable cover members associated with said supporting structure, as and for the purpose 110 specified.

2. In a safety cover for gondola cars, a 115 frame devised to be removably attached to the car body, means to lock said frame in place, a supporting structure carried by said frame, a series of independently movable cover members carried by said supporting structure, and means to lock said cover member rigidly to said frame, as and for the purpose specified.

3. In a safety device for gondola cars, a 125 frame associated with the car, means to lock said frame in position, a supporting structure carried by said frame, a series of independently movable cover members associated 130 with said frame, means for holding said cover member in open position against the tendency of gravity to close them, and means to lock said cover member in a closed position, as and for the purpose specified.

4. In a safety cover for gondola cars, the combination with a car body of a frame to be associated therewith, means to secure said frame to said car body, a supporting structure rigidly mounted on said frame, a series of independently movable cover members associated with said supporting structure, means for holding all of said cover members elevated in open position against the tendency of gravity to close them, and means to lock said cover members rigid with respect to said frame and said supporting structure, as and for the purpose specified.

5. In a safety cover for gondola cars, the combination with a car body, of a frame associated with said car body, means to secure said frame to said car body, supporting rods extending longitudinally of and in spaced relation to said car body above the center of the latter, means on said frame to support said rods, a series of independently movable cover sections movably mounted on said rods and adapted to open and close, and means for locking said cover sections in closed position, as and for the purpose specified.

6. In a safety cover for gondola cars, the combination with a car body, of a frame to be associated therewith, means to secure said frame in position, a supporting rod arranged centrally of and extending in spaced relation to said car body, a series of independently movable cover members carried by said rod, and means to hold said cover members in an open position against the tendency of gravity to close the same, as and for the purpose specified.

7. In a safety cover for gondola cars, the combination with a car body, of a frame to be associated therewith, means to secure said frame in place, supporting rods carried by and extending longitudinally of said frame in spaced relation to said car body and above the longitudinal center of the latter, a plurality of independently movable cover sections mounted on said rod, oppositely projecting securing arms supported by said frame, means carried by said cover members to engage with said securing arms, whereby said cover members may be held in an open position, and means to lock said cover members in a closed position, as and for the purpose specified.

8. In a safety cover for railway rolling stock, the combination with an open top body, of a frame thereon, means to secure said frame in position on said body, supporting rods extending longitudinally of said body and arranged in spaced relation thereabove, means carried by said frame to support said rods, a series of independently movable cover sections mounted on said rods, supporting means associated with the aforesaid rods, oppositely projecting securing arms on said supporting means, rings on said cover members to engage with said securing

arms whereby said cover members will be maintained in an elevated position, and means to lock said cover members in a closed position, as and for the purpose specified.

9. In a safety cover for gondola cars, the combination with a car body, of a frame associated therewith, means to secure said frame in place on said body, rods connected respectively to the ends of said frame and extending upward, other rods connected to the upper ends of said first mentioned rods, brace means for said first mentioned rods, means connecting the inner ends of the second said rods, brace means for said last mentioned connecting means, a series of independently movable cover members supported by the second said rods, and means to lock said cover members in a closed position, as and for the purpose specified.

10. In a safety cover for gondola cars, the combination with an open top car body, of a frame associated therewith, means to secure said frame in place, rods affixed to the ends of said frame, other rods connected with said first mentioned rods and extending substantially at right angles with respect thereto, brace means for said first mentioned rods, means connecting the inner ends of said last mentioned rods, brace means for said last mentioned connecting means, a series of independently movable cover members carried by said last mentioned rods, means to hold said cover members elevated in an open position, and means for securing said cover members when in a closed position, as and for the purpose specified.

11. In a safety cover for gondola cars, the combination with a car body of a frame associated therewith, means to lock said frame in position on said car body, a substantially vertical rod connected to one end portion of said frame and extending upwardly with respect thereto, a joint at the upper end of said rod, other rods connecting said joint and the side portions of said frame, a supporting rod having one end connected with said joint and extending substantially at right angles with respect to said first mentioned rod, a joint connected to the inner end of said supporting rod, other rods connecting said last mentioned joint to opposite sides of said frame, other rods connecting said last mentioned joint with the end of said frame opposite to the first said end, a plurality of independently movable cover members carried by said supporting rod, means to retain said cover members in an open position, and means to lock said cover members in a closed position, as and for the purpose specified.

12. In a safety cover for gondola cars, the combination with a car body of a frame to be associated therewith, means on the car body to support said frame, means to lock said frame in position on its supporting

means, rods affixed to the end portions of said frame and extending upwardly with respect thereto, joints at the upper ends of said rods, inclined rods connecting said joints with the sides of said frame, supporting rods each having their ends affixed to said joints respectively, brace rods connecting said joints respectively with the side portions of said frame, stay rods connecting one of said joints with the ends of said frame, a series of independently movable cover members mounted on said supporting rods, means car-

ried by said inclined rods for supporting said cover members when in a closed position, and means to hold said cover members in open position, as and for the purpose specified.

In testimony whereof I affix my signature in presence of two witnesses.

CORNELIUS M. GEIGER.
